UNITED STATES PATENT OFFICE.

JOHN L. McMILLAN, OF SYRACUSE, NEW YORK.

TELEPHONE ATTACHMENT.

1,212,785.

Specification of Letters Patent. Patented Jan. 16, 1917.

Application filed May 8, 1914. Serial No. 836,639.

To all whom it may concern:

Be it known that I, JOHN L. McMILLAN, a citizen of the United States, residing at Syracuse, in the county of Onondaga and State of New York, have invented certain new and useful Improvements in Telephone Attachments, of which the following is a specification.

My invention relates to sound amplifying attachments for telephones and resides in certain features of arrangement and construction which permit automatic actuation of the telephone receiver hook switch without requiring the attachment of any parts to either the receiver or receiver hook. An additional advantage is the ready disconnection of the amplifier by merely removing the receiver from the hook for use in the ordinary way.

In prior amplifying devices the amplifier has usually been connected to the receiver and the devices for operating the receiver hook switch have commonly been connected with the receiver hook. It is often desirable to use the telephone without the amplifier, which cannot readily be done when it is connected to the receiver, and the telephone companies usually forbid the attachment of any mechanisms to the working parts of their telephones, so that the use of these prior devices has been somewhat limited.

Broadly stated my invention comprises an amplifying horn which is so mounted as to be manually movable first to contact with the ear-piece of the receiver as the latter hangs on the hook, and then by a continued movement to lift the receiver and permit upward movement of the hook so that the telephone is connected. An impositive latching device may be provided to hold the horn in its upper and lower positions.

The device is applicable to any telephone in which the receiver hangs on a switch-operating hook but I illustrate it as applied to the familiar "desk set" in the accompanying drawings, in which—

Figure 1 is a perspective view of a device embodying my invention, the position of the telephone being indicated in dotted lines; Fig. 2 is a fragmentary elevation of a telephone with my invention attached, the receiver being in its lower position with the telephone disconnected; Fig. 3 is a view similar to Fig. 2 showing the receiver lifted to connect the telephone; Fig. 4 is a section

of the complete device; and Fig. 5 is a section on the line 5—5 of Fig. 4.

The device is supported on a base plate 6 provided with screw held clamp fingers or lugs 7 to engage the base 8 of the telephone.

An upstanding bracket or case 9 on the base plate carries a fulcrum 10 for a hanger 11 in which is clamped the neck tube 12 of the resonator horn. This neck tube 12 extends forward between the arms of a latch or retaining spring 13 of the form clearly shown in Fig. 5, the spring operating as an impositive latch to hold the neck tube in its raised and lowered positions. At its forward end the neck tube 12 curves upwardly and terminates in a cup 14 having a pad 15, the cup and pad being of such proportions and so positioned with relation to a telephone clamped on the base 6 as readily to contact with the ordinary ear-piece 16 of the telephone receiver 17, as this hangs on the hook 18. A handle 19 is provided to permit ready manual lifting and lowering of the neck tube. The rear end of the neck tube 12 is curved upward and forward at 20 and carries a removable amplifying horn 21 which may be of any desired shape.

When the tube 12 is in its lowered position it is impositively held by the spring 13. The cup 14 and pad 15 are then virtually out of contact with the ear-piece 16. In using the telephone the receiver may either be lifted from the hook and placed to the ear in the usual way or the handle 19 may be lifted to raise the neck tube 12 until it latches in its upper position. In such upper position the ear-piece 16 will rest squarely on the pad 15 and the receiver 17 will be so elevated as to release hook 18 and cause its connected switch to connect the telephone. This brings the diaphragm of the receiver into direct connection with the neck tube 12 and the connected amplifier or resonator 21 so that the telephone may be heard at a considerable distance.

The advantages of the device will be obvious, the features of particular importance being the possibility of use in the ordinary way and the avoidance of all mechanical connections to any of the working parts of the telephone.

Having thus described my invention, what I claim is:—

1. The combination with a telephone desk set including a base, a receiver hook switch supported thereby and a receiver carried by

said hook switch; of a separate and detachable support for said base; an amplifying horn pivotally mounted on said support and having a mouth piece adapted to move into 5 operative relation with the ear piece of the receiver and then lift said receiver to free the hook switch; and a latch for holding said horn in said last named position.

2. The combination with a telephone desk 10 set including a base, a hook switch carried thereby and a receiver supported by the hook switch; of a supporting member releasably clamped to said base; a sound amplifying horn pivotally mounted on said

support having a mouth piece movable by 15 the movement of said horn to engage the ear piece of said receiver and then lift the latter to free the hook switch; and an im-
positive latch for alternately holding said horn in and out of its receiver elevating po- 20 sition.

In testimony whereof I have signed my name to this specification in the presence of two subscribing witnesses.

JOHN L. McMILLAN.
